(57) **CLAIM**

The ornamental design for a furniture element as shown and described.

DESCRIPTION

FIG. 1 is a top, front, right side perspective view of our new design for a furniture element.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The appearance of any portion of the article between the break lines, represented by long-short-short dashed lines, forms no part of the claimed design.

The evenly spaced broken lines in FIGS. 1-7 indicate boundaries and form no part of the claimed design. Additional evenly spaced broken lines in FIGS. 4, 5, and 7 show portions of the furniture element, and form no part of the claimed design.

1 Claim, 6 Drawing Sheets
